UNITED STATES PATENT OFFICE

2,337,960

GAS INSTALLATION HOUSING

Eric Martin Anderson, Portland, Maine, assignor
to Utilities Distributors, Inc., Portland, Maine,
a corporation of Maine

Application September 30, 1942, Serial No. 460,285

4 Claims. (Cl. 312—112)

The present invention relates to improvements in gas installation housings, and has for an object certain improvements over prior mechanical Patent No. 2,278,232, granted March 31, 1942, and Design Patent No. Des. 127,783, granted June 17, 1941, as well as over other patents in this art.

The object of the invention is to dispense with any hinges and to enable the hood to be simply lifted off the back plate, and in which the act of placement of the hood projects a portion of the back plate through the hood to receive a padlock for securing the hood against unauthorized removal and subsequent tampering with the regulator and the valves.

Another object of the invention is to promote the accessibility of the regulators, valves and other parts housed within the hood by the simple expedient of unlocking the padlock and lifting off the hood.

A further object of the invention is the extremely low cost of manufacture of the device according to the present invention.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a perspective view, with parts broken away and parts shown in section, of an improved gas installation housing constructed in accordance with the present invention.

Figure 2 is a vertical central section taken through the device with parts broken away.

Figure 3 is a horizontal section taken on the line 3—3 in Figure 2.

Figure 4 is a front elevation of a modified form of the device, with parts broken away and parts shown in section, of the back plate detached, and

Figure 5 is a side edge view of same with regulator attached.

Referring more particularly to the drawing 10 designates the base or floor and 11 the side wall of a location where one or more gas bottles or containers 12 are situated. The hood 13 will conform in size and shape to the one or more gas bottles included in the installation. In the present instance this hood is shown as being generally of the form of a quarter sphere with an open bottom to closely fit about the upper part of the gas bottle or container 12 and with an open rear portion next the wall 11. The open open back portion of the hood is spanned by a

flat-bar 14 welded or otherwise secured to the side walls of the hood at the lower portion thereof and acting to support the hood in the channel support, of which 15 is the bottom wall, 16 the front flange and 17 the back wall. This channel support preferably is co-extensive in horizontal length with the width of the hood except that the side walls of the hood lie beyond the ends of the channel in order to seat the bar 14 firmly upon bottom wall 15. The front flange 16 is preferably given a slight outer flare to facilitate the entrance of the bar 14 into the channel as this bar 14 is given a slight turning motion as the hood is put into place and therefore the channel space between the walls 16 and 17 is preferably of a width somewhat in excess of the width of the bar 14 to allow the necessary clearance.

Screws or other fastenings 18 may be driven through holes in a portion of the back wall 17 which extends up above the flange 16 and into the wall 11 for the purpose of securing the channel support at the proper elevation.

A back plate or vertical strip 19 is welded or otherwise secured at its lower end to the channel support and at its upper end portion is affixed to the wall 11 by a screw or other fastening 20. At its upper end the back plate 19 is turned diagonally outward away from the wall 11 in position to receive an opening in the upper portion of the hood 20. A padlock 22 is secured in the perforation of the upwardly projecting end portion which locks the hood in place.

As shown in Figure 4 the back plate 19 is offset at 23 outwardly away from the wall and in this offset portion are located a number of keyholes or other openings 24 to receive the fastenings which secure the regulator 25 in place.

The locking bar 21 is at the top of the back plate 19 and the hood may be lifted off without the necessity for a hinge. Such construction cost is much lower than where hinges are involved. Hinges are apt to rust and deteriorate from this cause which disadvantage is eliminated. Without the use of hinges the hood can be removed entirely from the device so that the operator has access to the installation with much greater freedom. The back plate and channel support can be equipped with keyhole slots similar to the keyhole 24 for cooperating with the fastenings 18 and 19 if desired. The keyholes 24 punched in the back plate accommodate easy installation of the regulator 25.

The design of the hood may be round, square or of any other desired form. The drawing shows

only a single-cylinder installation but the invention is equally applicable to double-cylinder installations by simply extending the width of the same, no greater height or depth being required. The invention is also suitable for four-cylinder hoods.

The inclination of the locking bar 21 will cause the hood 13 to move downwardly and inwardly toward wall 11 at the same time so that clearance is desired for bar 14 in the channel support. The relative arrangement of the locking bar 21 and of the hood slot 26 will require a rocking movement of the bar 14 in the channel support and the clearance between wall 16 and 17 and the outward divergence of flange wall 16 will accommodate this rocking or rotary movement by the bar 14.

When the hood is in place the same cooperates with the container 12 and with the back wall 11 to completely house the regulator, valves and other equipment against unauthorized tampering.

It is obvious that various changes and modifications may be made in the details of construction and design of the above specifically described embodiment of this invention without departing from the spirit thereof, such changes and modifications being restricted only by the scope of the following claims.

What is claimed is:

1. In a gas installation housing, a channel support, a back plate connected with said support and comprising a narrow vertical strip secured to an intermediate portion of said channel support with fastening means at its upper portion to secure the back plate to a wall or the like, said narrow vertical strip having at its upper end an upstanding diagonal out-turned end, a hood completely detachable from said support and back plate having a slot in its upper portion to freely slide over said diagonal out-turned end, a bar extending across the lower inner portion of said hood adapted to removably seat in said channel support, and removable locking means for engaging in the upper part of said diagonal out-turned end above the hood.

2. In a gas installation housing, a back plate, a channel support, said back plate and channel support both having means for receiving fastenings to attach the same to a wall or other sup-

port, said channel support having a bottom wall and a front flange spaced forwardly from the back plate, said channel support being open at its upper portion, said front flange extending diagonally upwardly and outwardly from said bottom wall, said back plate having at its upper portion a diagonal out-turned end, a hood having a slot in its upper inner portion positioned relatively to said diagonal out-turned end to slide thereon in a diagonal direction in the positioning and removal of the hood, a flat bar extending across the lower inner portion of the hood and affixed thereto with its edgewise dimensions disposed substantially vertically in the home position of the hood, said bar being thin relatively to said base of the channel and adapted to have a rocking movement in moving into and out of said channel permitted by the outwardly flaring upper portion of the front flange of said channel support, and locking means for engaging with the upper part of said diagonal out-turned end above the hood.

3. In a gas installation housing, a hood shaped generally like a segment of a sphere having open portions at its rear and bottom and provided with a slot in its upper inner central portion, a back plate adapted to be secured to a wall or other support having a diagonal out-turned end for engaging loosely through said slot without supporting the hood, a flat thin bar extending across the lower inner portion of the hood, a channel support secured to said back plate and having means to secure the same to a wall or the like support positioned to receive said bar and to support said hood through said bar, said channel support having a forwardly flaring front flange.

4. In a gas installation housing, a hood having an open back and an open bottom with a slot in its upper rear portion, a supporting bar secured to the lower inner portion of the hood, a channel support having outwardly flaring front flange and being open at its top to receive said bar, and a back plate secured to said channel support, said back plate adapted to be secured to a support and having a diagonal out-turned upper end portion projecting loosely through said slot, and means for engaging the upper part of said diagonal out-turned end to secure the hood in place.

ERIC MARTIN ANDERSON.
